UNITED STATES PATENT OFFICE.

ROBERT WILLIARD PAIN, OF NEW YORK, N. Y., ASSIGNOR TO THE AEOLIAN COMPANY, A CORPORATION OF CONNECTICUT.

ACTUATING MECHANISM FOR PNEUMATICALLY-OPERATED MUSICAL INSTRUMENTS.

No. 872,678.

Specification of Letters Patent.

Patented Dec. 3, 1907.

Application filed January 23, 1907. Serial No. 353,581.

To all whom it may concern:

Be it known that I, ROBERT WILLIARD PAIN, a citizen of United States, and resident of borough of Manhattan, city, county, 5 and State of New York, have invented certain new and useful Improvements in Actuating Mechanism for Pneumatically-Operated Musical Instruments, of which the following is a specification accompanied by 10 drawings.

This invention relates to actuating mechanism for pneumatically operated musical instruments, more particularly to improvements in secondary or striking pneumatics 15 for actuating sound producing devices for instruments.

The objects of the invention are to increase the rapidity of recovery or inflation of the striking pneumatic after the sound producing device has been actuated, and avoid the time interval due to slow ingress of air under atmospheric pressure as the movable board of the pneumatic resumes its normal position when suction is relieved.

25 Further objects of the invention will hereinafter appear and to these ends the invention consists of actuating mechanism for carrying out the above objects embodying the features of construction, combinations of 30 elements and arrangement of parts having the general mode of operation substantially as hereinafter fully described and claimed in this specification and shown in the accompanying drawings, in which,—

35 Figure 1 is a longitudinal vertical sectional view of actuating mechanism embodying the invention; Fig. 2 is a longitudinal elevation partly in section of the mechanism; Fig. 3 is a view similar to Fig. 1, in which the secondary 40 pneumatic is shown in a different position or partially collapsed; Fig. 4 is a top plan view of the secondary pneumatic showing the secondary valve.

45 Referring to the drawings, A represents a secondary or striking pneumatic for a pneumatically actuated musical instrument, and B is the rod for actuating the sound producing device, it being understood that these parts comprise portions of the mechanism of 50 the mechanical musical instrument having the usual tracker board, a perforated music sheet for controlling the admission of air to the ducts C, primary pneumatics D adapted

to be actuated through the agency of the air in said ducts and operating valves E which 55 control the secondary pneumatics A.

In the present instance the secondary pneumatic A is adapted to be operated by suction, and when air under atmospheric pressure is admitted through one of the ducts 60 or tracker board passages C to the lower side of the primary pneumatic D, the suction in the chamber F will cause said pneumatic to close the valve G and open the primary valve H, thereby admitting air under atmospheric 65 pressure to the lower side of the pneumatic I so that suction in the chamber J will cause said pneumatic to open the suction or main valve E and apply suction to the secondary pneumatic A to cause it to actuate one of the 70 sound producing devices. The valve E is preferably constructed of suitable flexible material and is secured at the point K at one side of the valve opening L so that the valve is in effect hinged at the point K, although 75 any other suitable construction may be provided. When the tracker board passage C is closed again the valve E is automatically closed in the usual manner, and the primary valve H is also closed. A primary valve 80 opening O is provided in the immovable board P of the secondary pneumatic, and said opening O is adapted to be controlled by the primary valve H, said valve being preferably of flexible material and secured at the 85 point Q to the valve chest, thereby forming in effect a hinged valve. When the secondary pneumatic A is to be actuated for striking purposes, the primary valve H closes the valve opening O and prevents the admission 90 of air to the secondary pneumatic A, and when the primary valve H falls, atmospheric air is admitted through the opening O to the secondary pneumatic to permit the movable board R to resume its normal position.

95 One of the objects of this invention is to enable air under atmospheric pressure to be admitted more freely to the secondary pneumatic A after the suction has been relieved, and thereby permit the movable board R to 100 resume its normal position more quickly than heretofore. The movable board R is provided with a secondary valve opening S and the valve T controlling the same, which is adapted to be operated in accordance with 105 the tension of the air in the secondary pneu-

matic A. In the present instance this secondary valve T comprises a flexible sheet or strip of material, as for instance leather or any other suitable material, which is preferably secured at one end to the movable board at U while the other end is left free and is connected to a retracting spring V, suitably secured to the movable board R as by means of the staple W. Preferably the sheet of flexible material forming the valve T is provided with a cleat X to which the spring is connected. As shown, the outer portion of the movable board R is dished or cupped at Y around the valve opening S so that when the flexible sheet T is pulled taut by the spring V, there will be an opening between the sheet T and the bottom of the dished portion Y, affording provision for the entrance of air under atmospheric pressure through the valve opening S to the secondary pneumatic.

In Fig. 3 the secondary pneumatic is shown partially collapsed as it is about to strike when suction is applied through the opening L, in which case the flexible valve T will be drawn or sucked into the dished portion Y of the movable board R, thereby tightly closing the secondary valve opening at S, and preventing admission of air. As soon as suction is relieved, air enters through the primary valve opening O and the tension of the spring V is relieved, which thereby pulls the flexible secondary valve T tight again, as shown in Fig. 1, thereby opening the secondary valve opening S and permitting air under atmospheric pressure to freely enter the secondary pneumatic, which enables the movable board R to resume its normal position quickly without the time interval due to the slow ingress of air, which would occur with a small primary valve opening H. Preferably the bottom of the valve chest is formed of suitable flexible material Z, which

is sufficiently elastic to aid in the rapidity of action of the valves.

The construction of the actuating mechanism in accordance with this invention forms in effect pneumatic means for increasing the rapidity of action of the secondary pneumatic. The secondary valve T is adapted to automatically close when suction is applied to the secondary pneumatic, and open automatically when suction is relieved. This secondary valve T also excludes atmospheric air from the secondary pneumatic when striking and admits atmospheric air freely upon recovery.

I claim and desire to obtain by Letters Patent the following:

1. In actuating mechanism for pneumatically operated musical instruments, the combination with the striking pneumatic having movable and immovable boards provided with valve openings, of a sheet of flexible material adapted to control the valve opening of the movable board, and operating automatically to close and open in accordance with the tension of the air in the secondary pneumatic.

2. In actuating mechanism for pneumatically operated musical instruments, the combination of a pneumatic having a movable board dished on its outer side and provided with a valve opening in said dished portion of the board, and a flexible valve in the form of a sheet of material fastened to the board at one side of the valve opening, a spring being connected to the other free end of said sheet of material to maintain the valve normally tight across the dished portion of the board.

In testimony whereof I have signed this specification in the presence of two subscribing witnesses.

ROBERT WILLIARD PAIN.
